IMPACT DEFLECTOR FOR TRACK WORK
Henry H. Talboys, Milwaukee, Wis., assignor to Nordberg
Manufacturing Company, Milwaukee, Wis., a corpora-
tion of Wisconsin

Filed Aug. 5, 1960, Ser. No. 47,630
6 Claims. (Cl. 15—55)

This is a continuation-in-part of Serial No. 29,605,
filed May 17, 1960.

This invention is in the field of track sweepers and is
concerned with a deflector assembly positioned ahead of
the sweeper so that ballast propelled forwardly by the
sweeper will be deflected and thrown or placed outside
of the rails.

A primary object of the invention is a deflector which
will give the propelled ballast both a vertical and a hori-
zontal component of movement.

Another object is a method of handling and placing
ballast.

Another object is a combination sweeper and deflector
which places the ballast properly with a minimum of
effort.

Another object is a deflector which places all or sub-
stantially all ballast outside of the rails in one step.

Another object is a ballast deflector which may be
manually set off or on the rails.

Another object is a ballast deflector of the above type
with removable wear plates.

Another object is a wear plate for a ballast deflector.

Other objects will appear from time to time in the en-
suing specification and drawings in which:

FIGURE 1 is a perspective of a track sweeper and de-
flector;

FIGURE 2 is a top view of the deflector with the cover
plates removed and without wheels;

FIGURE 3 is a side view of the deflector;

FIGURE 4 is a front view with the left side deflector
plate removed; and

FIGURE 5 is a top view, on a reduced scale, with the
right half of the upper frame removed.

As shown in FIGURE 1, the unit is made up primarily
of three main parts, a vehicle 10, an impeller 12 on the
front of the vehicle, and a deflector or baffle 14 ahead
of the impeller. The details of the vehicle and impeller,
as such, are not important to this invention. The vehicle
may have a suitable power unit for self-propelling the
entire unit as well as operating the impeller. The im-
peller is rotated in a direction to sweep or propel loose
ballast forwardly, as indicated by the arrow in FIGURE
3, and the entire assembly moves to the right in FIGURE
1. The impeller may be divided into three sections, a
center section and two side sections with gaps between
them so that they will fit between the tie ends and straddle
the rails. It can be said that the impeller operates be-
tween the tie ends. The impeller may be made of sepa-
rate paddles, for example four circumferentially spaced,
radially disposed blades or paddles which are solid, flexi-
ble, and resiliently stiff strips adjustably and removably
connected to a center shaft or rotor.

The deflector or baffle 14 is made up of two main
parts, first a main frame, indicated generally at A, for
example in FIGURES 3 and 4, and, second a top frame
or cover which is removably mounted laterally across
the top of the main frame and indicated generally at B,
for example in FIGURES 3 and 5. The main frame is
mounted on suitably flanged wheels 150 on an axle 152.
Vertical angles or corner posts 154 on each side rise from
the axle to longitudinal top angles 155 connected by a
crosspiece 156 in FIGURE 5. The main frame includes
lower longitudinal angles 158 on each side which are

2

connected, as by welding or otherwise, to the vertical
corner posts. These extend rearwardly and are con-
nected to the top angle 155, on each side, by a strap or
flat 160. The center of the axle may be connected by
5 two vertically disposed angles 162, somewhat spaced from
each other, to a main center brace 164 or the like, which
may take the form of an upside down channel, extending
10 rearwardly. I position an angle 168 in FIGURES 2 and
4 laterally between the lower angles 158 with a strap or
angle 170 in FIGURE 4 extending up from the middle
of brace 168 and connected to the bottom of the main
center brace 164.

It will be noted that the main center brace 164 is some-
what longer and extends farther rearwardly than the side
15 top frame members 155. Also, the lower frame mem-
bers 158 are somewhat longer than the upper frame
members 155, but not as long as the main center brace
164. I position flats or strips 172 extending from the
20 rear end of the main center brace 164 outwardly and
forwardly across the rear end of the top side frame mem-
bers 155 and outwardly beyond it somewhat as at 174 in
FIGURE 5. I also connect another flat 176, as shown
in FIGURE 4, to or adjacent the rear edge of the first
25 diagonal flat 172 and about the same length, on both sides
but sloping down.

I mount the upper frame or cover on the main frame
which includes rear and forward angles or frame mem-
bers 178 and 180 having pipes 182 connected between
30 their ends to make up a somewhat rectangular frame.
Diagonally disposed angles 184 are suitably braced by
longitudinal angles 186 with a center longitudinal angle
188 extending between the main frame members. I may
35 mount a stud 190 on the forward angle on each side to be
connected to the vehicle by suitable bars 192 or the like,
shown in FIGURE 1, through a cotter key 194 so that the
unit may be adjusted as to height, inclination, and pos-
ition. The upper frame may be bolted to the lower or
40 main frame in a number of places, for example at 198,
200, 202, 204, 206 and 208 in FIGURE 2. I position
covering plates 210, as shown in the left half of FIGURE
5, between the main frame and top frame which conform
45 along one edge 212 more or less to the diagonal strips or
flats 172 and are held in place by a plurality of bolts 214
or the like.

I attach deflector or divider plates 216 to the inclined
flats or strips 176, one on each side sloping inwardly
50 toward each other and abutting at an inclined edge 218.
The outer edge 220 of each may be at right angles or
roughly perpendicular to the top edge. The top edge is
connected by a plurality of bolts 222 or the like to the
inclined flats 176. I position a bracket 224 adjacent the
55 inner edge 218 of each, to be connected to each other.
Toward the outer edge 220, I position another bracket 226
which is connected to the end of the side frame member
158. The lower edge 228 of each plate may be generally
straight and parallel to the upper edge. I provide a cut-
60 out 230 toward or adjacent the outer edge having a slot
232 rising somewhat. I then bend a portion of the lower
edge from the top of the slot toward the bottom of the
inner edge, along a line 234, the bend being made up-
wardly at a suitable angle, say 35° or so to the plane
65 of the plate to form a wing deflector 235. The outer portion
of the lower edge of the plate is removed, as at 236.
The two plates may be the same except symmetrical op-
posites.

To cover or mask the gap between the rear edge of the
deflector and the forward end of the impeller on the
70 vehicle, I may attach suitable flexible strips of rubber or
the like laterally across the rear edge of the upper frame,
as at 238, by bolts 214, so that the material thrown up

by the impeller will not injure anyone or damage other equipment.

As shown in FIGURE 1, I may also position an intermediate removable deflector 240 on each side connected to the upper frame by a T-slot connection 242. The lower edge of each such deflector may be provided with a flexible blade or panel 244 removably connected, as at 246, so that it may be replaced when excessively worn. It will be noted in FIGURE 1 that the lower end of the flexible piece or section may engage the ballast. It should also be noted that the inner edge of the removable deflector stops just about at the rail. The removable deflectors 240, as such, may be considered as working or cooperating with the outer sections of the impeller outside of the rails over the tie ends.

The ballast is propelled forwardly by the impeller and is deflected outwardly by the divider plates. The removable deflectors 240 on each side are disposed generally parallel to the deflector plates 216 but spaced from them to define outlets or channels, as at 248 in FIGURE 1. The space behind the removable deflector also defines another outlet or channel, indicated generally at 250 in FIGURE 1.

I may also mount a roller 252 on top of the impeller frame to engage an angle 254 mounted on and projecting rearwardly from the top of the deflector. It should be noted that the flat edge of the angle is opposite the roller and the angle tilts down at 256 so that the roller will tend to center itself. Thus the operator may raise the impeller which, in turn, will raise the rear end of the deflector so that adjustment of the deflector may be made to either raise or lower the rear of the deflector prior to a sweep. This may also be used to raise the deflector at crossings, switches, etc.

The use, operation and function of my invention are as follows:

I provide a deflector structure which is constructed and adapted to roll on the track ahead of a sweeper which propels loose ballast or the like forwardly. The deflector is constructed to deflect the material freely to either one side or the other. The deflector plates themselves are positioned at an inclined angle, a double inclination, inclined first to the vertical and second to the direction of the track. For example, the plates may be disposed roughly at 34° or 35° to the direction of the track and also 34° or 35° to the vertical. The angle of inclination to the vertical is important since the material propelled forwardly will be rising somewhat. Upon striking a deflector plate, it will be given an additional vertical component of movement due to the inclination of the plates. It will also be given a lateral component of movement in accordance with the lateral inclination of the plates. The best operation is for the material to strike the plates and deflect outwardly and upwardly with sufficient velocity to clear the rails after deflection. The spacing between the deflector plates and the side deflectors 240 is such, relative to the lateral angle of the deflector plates, that the material will normally fly out through the opening or passage 248 without striking the back of the removable deflector. At the same time, the material outside of the rails on top of the tie ends will be propelled forwardly and will be deflected outwardly by the removable deflectors. I may operate the unit without the removable deflectors in which case the inclined deflector plates will receive all of the ballast.

The removable deflectors may or may not be inclined at the same angle, both to the vertical and to the rails, as the divider plates 216. Or they may be more or less vertical, somewhat as shown in FIGURE 1, since it is not necessary that they give the ballast a vertical component of movement. In a sense the removable deflectors 240 only have to deflect the ballast outwardly and not vertically.

Also, the upper or top deflector frame extends out beyond the sides of the lower or main frame. For example,

in FIGURE 2 the upper frame or top cover may be considered to extend out just about to the tie ends. The angle of inclination of the deflector plates 216 is such that the ballast rises enough, after bouncing off of the inclined deflector plates 216, so that it hits the cover plates 210 at a point about half way out and is deflected down. Thus, when the ballast passes over the rails, it is moving down and will land outside of the rails. Depending upon where the ballast is initially positioned between the rails, it may not strike the cover plates 210 until after it is beyond the rails.

In a sense, the ballast is deflected twice, first against the inclined plates so that it moves out and up, and next against the flat overhead or cover plate, so that it is knocked down but is allowed to finish its outward travel. The most desirable is a double bounce, and this is true for the vast majority of the ballast. But it should be understood that some of the ballast will not rise sufficiently after the first bounce and will not hit the top cover plate. But this is not important since it will still land outside of the rails.

It is important to move the ballast using as little energy as possible. Having the ballast strike the deflector plates and fly to either one side or the other in free flight without again having to be picked up by the impeller is the most efficient.

The deflector and cover plates are replaceable items since they will be subject to wear and, as such, I preferably bolt them to the frame or attach them by any suitable means which will let them be replaced easily. The over-all unit may be tilted either up or down about the wheels 150 to vary the vertical inclination of the plates which in turn will somewhat vary the rise of the ballast after the first bounce.

As viewed from above, the plates cross the rails at a substantial angle, for example at about a 34° or 35° angle, so that the material propelled forward by the impeller will be deflected out to the side at a substantial angle, for example, at about 68° to 70° to the rails. As shown in FIGURE 3, the plates are tilted substantially to the vertical, for example of the order of 34° or 35°, when viewed on edge, to give the vertical movement to the ballast.

The upper plates in the top frame are also replaceable items since they become worn. And I preferably bolt them in place. The entire deflector may be made sufficiently light so that it may be manually picked up and either removed or put on the track. The bars 182 on each side may be used as handles either in putting the deflector on the track or taking it off, or they may be used to lift the top frame off of the main frame when the various wear plates are being replaced.

The wing deflectors 235 are generally inside of the rails and the cut-outs 230 formed out of a part of the wings and also a part of the deflector plates fit over the rail. Ballast that is not thrown high enough by the impeller will hit the wings, and they in turn, due to their steep inclination, make sure that this ballast will get up above rail height. In a sense, the part of the ballast which hits the wings may bounce three times, first against the wings, second against the main divider plate, and third against the overhead. In some situations the third bounce may not take place. But, in any event, the wings make sure that most, if not all, of the ballast gets up to the main divider plate and above the rails.

While I have shown and described the preferred form of my invention, it should be understood that suitable additional modifications, changes, substitutions and alterations may be made without departing from the invention's fundamental theme. I, therefore, wish that the invention be unrestricted, except as by the appended claims.

I claim:

1. In a sweeper for use on railroad track and the like, a vehicle adapted to move along the track, a rotary impeller on the front of the vehicle spanning the rails and

constructed to propel ballast forward freely from the roadbed in a lateral area generally between the tie ends, and a deflector positioned forward of the impeller having deflector plates positioned on the general level of the impeller, each plate having its outer edge forward of its inner edge and its top edge forward of its bottom edge, and disposed at a sufficient angle inclined both to the direction of the rails and to the vertical so that ballast propelled forward by the impeller, upon striking one of the plates, will be deflected both outwardly and sufficiently upwardly to otherwise clear the rails in free flight, said deflector defining an unencumbered free path inclined outwardly and forwardly over each rail for the deflected ballast.

2. The structure of claim 1 further characterized in that the deflector plates merge at a point generally midway between the rails and extend forwardly and outwardly therefrom spanning each rail, a cut out portion in each plate over the rail, and a portion bent rearwardly and upwardly from the general plane of the plate on the lower edge of the plate inside the rail.

3. The structure of claim 1 further characterized by, and including, removable deflector plates positioned outside of the rails, generally over the tie ends, and spaced rearwardly from the first mentioned deflector plates.

4. The structure of claim 1 further characterized by, and including, a generally horizontal cover plate over the deflector plates on a level generally with the top of the impeller and overlying the rails on both sides so that the ballast deflected upwardly by the deflector plates will be deflected down outside of the rail.

30

5. The structure of claim 1 further characterized by, and including, a wing portion on each deflector plate along the lower edge thereof, upstruck from the general plane of the plate and tapering inwardly toward the inclined inner edge of each said deflector plate, each wing portion being inclined at an angle to the horizontal so that the portion thereof adjacent the outer edge of the deflector plate extends to a position generally above the top of the rails and the portion thereof adjacent the inner edge of the deflector plate is positioned generally below the top of the rails.

6. The structure of claim 1 further characterized by, and including, a removable deflector plate on the outside of each rail, positioned generally over the tie ends, and spaced rearwardly from the first mentioned deflector plates, each such removable deflector plate having a flexible element mounted along its lower edge extending downwardly therefrom into contact with the ballast on the tie ends to perform a ballast smoothing operation on the tie ends when the vehicle and deflector move along the track.
